*Primary Examiner—Stella Reid
Attorney, Agent, or Firm—Charles F. Costello, Jr.*

[57] CLAIM

The ornamental design for a suture package, as shown
and described.

DESCRIPTION

FIG. 1 is a front perspective view of a suture package in
folded condition;

FIG. 2 is a rear perspective view thereof;

FIG. 3 is a front elevational view thereof, in unfolded
condition;FIG. 4 is a front elevational view of an insert for the
suture package; and,FIG. 5 is a perspective view illustrating the folding
sequence of the suture package.The broken lines on the surface of the article in FIGS.
1, 3 and 5 represent perforations for folding the suture
package.
